UNITED STATES PATENT OFFICE

ERWIN HOFFA, OF HOCHST-ON-THE-MAIN, JENS MÜLLER, OF HANAU-ON-THE-MAIN, AND FRITZ MÜLLER, OF HOCHST-ON-THE-MAIN, GERMANY, ASSIGNEES TO GENERAL ANILINE WORKS, INC., OF NEW YORK, N. Y., A CORPORATION OF DELAWARE

PROCESS OF CONVERTING ARYLCARBOXYAMINO-O-THIOLYCOLIC ACIDS INTO HYDROXYTHIONAPHTHENE COMPOUNDS

No Drawing. Application filed August 9, 1927, Serial No. 211,852, and in Germany April 16, 1927.

This invention relates to a process for the production of hydroxythionaphthene compounds from arylcarboxyamino-o-thioglycolic acid compounds.

5 We have found as a general reaction, that arylcarboxy-amino-o-thioglycolic acids as described in Patents, 1,703,145 and 1,725,080 are directly transformed into the corresponding hydroxythionaphthene-compounds 10 when treated at an elevated temperature with a suitable alkaline acting agent, particularly with caustic alkali solutions.

The new process proceeds probably according to the following scheme:

Of particular interest is the procedure

25 wherein X represents one of the substituents hydrogen and alkyl, and Y represents one of the substituents halogen and alkyloxy.

This new reaction is surprising, because it is 30 known (see British specification No. 11173 of 1906), that the cyanaryl-o-thioglycolic acids (the starting material for the carboxyamino-compounds) are converted into aminothionaphthene-carboxylic acids. According 35 to general assumption this reaction runs in such a way that the carboxyaminothioglycolic acids are formed as intermediates and then split off water in *statu nascendi*.

The thus formed aminothionaphthene-carboxylic acids are very stable to alkaline acting agents and can only be converted advantageously into the corresponding hydroxythionaphthene compounds by treating them with dilute acids (cf. Friedländer, Liebigs Annalen, Vol. 351, page 417). Our new process proves, that the above mentioned assumption is erroneous. Our new process is adapt-

ed to the direct manufacture on a technical scale of the hydroxythionaphthene compounds in an almost chemically pure state with an excellent yield. From these hydroxythionaphthene compounds the corresponding 55 thioindigo dyestuffs can be produced in the usual manner by oxidation without previously isolating the hydroxythionaphthene compounds.

In the present new reaction of conversion 60 of arylcarboxyamino-o-thioglycolic acids into ring compounds, as described herein and as set forth in the following claims, it is to be understood that we do not wish to limit ourselves to the use of an alkali as strictly 65 defined. The same result will be produced and substantially the same products obtained by using alkaline sulfides, alkaline polysulfides, alkaline earths, such as milk of lime, any of which are in this process equivalents 70 of alkalies.

The following examples serve to illustrate 75 our invention but they are not intended to limit it thereto, the parts being parts by weight:

(1) 245 parts of 1-methyl-5-chlorobenzene-2-carboxyamino-3-thioglycolic acid of the probable formula

85 are dissolved in 4000 parts of water and 54 parts of sodium carbonate and mixed with 180 parts of caustic soda. The solution is heated to 80° C. and kept at this temperature for 7 hours, whereupon a difficultly soluble 90 product consisting for the most part of the compound having most probably the formula

separates which is colored red by the coloring-matter produced by atmospheric oxida-

tion. By oxidizing the resulting hydroxythionaphthene and hydroxythionaphthene carboxylic acid respectively by means of one of the usual oxidizing agents the 4-4'-dimethyl-6-6'-dichlor-thioindigo may be obtained without having previously to isolate the reaction product.

(2) 10 parts of 1-methyl-5-chlorobenzene-2-carboxyamino-3-thioglycollic acid are heated in a pressure-vessel for 5 hours to 140° C. with 100 parts of water and 30 parts of calcium hydroxide. The mass is filtered, while hot, and by oxidizing the solution the same dyestuff as that produced according to Example (1) may be obtained without having previously to isolate the hydroxythionaphthene.

(3) 10 parts of 1-methyl-5-chlorobenzene-2-carboxyamino-3-thioglycollic acid are heated in a pressure-vessel for 5 hours to 140° C. with 100 parts of water and 50 parts of barium hydroxide. The further operations for obtaining the hydroxythionaphthene and the dyestuff therefrom may be carried out as indicated in Example (2).

(4) 30 parts of crystallized sodium sulfide are melted at 90° C. Into this melt are introduced 10 parts of 1-methyl-5-chlorobenzene-2-carboxyamino-3-thioglycollic acid and the whole is heated to 90-100° C. until the evolution of ammonia has ceased. After the melt has cooled it is diluted with salt water and filtered by suction. By oxidizing the compound thus obtained the 4-4'-dimethyl-6-6'-thioindigo is obtained without having previously to isolate the hydroxythionaphthene.

(5) 82 parts of 4-ethoxybenzene-1-carboxyamino-2-thioglycollic acid having the probable formula

45 are heated to 90° C. with 300 parts of caustic soda solution of 40° Bé.; there are then added thereto 180 parts of water and the resulting pasty mass is heated for one hour to 100° C. The evolution of ammonia, which occurs during this operation, will have decreased at the conclusion of the time period. The whole is then dissolved in 3000 parts of water and by oxidizing the resulting solution the 6-6'-diethoxythioindigo is obtained without having previously to isolate the 6-ethoxy-3-hydroxythionaphthene which has the probable formula

We claim:

65 1. The process which comprises causing an

alkaline acting agent to act upon a compound of the following general formula:

while heating the reaction mixture.

2. The process which comprises causing an alkaline inorganic alkali forming metal compound to act upon an aqueous solution of a compound of the following general formula:

80

wherein X represents hydrogen or alkyl and Y stands for halogen or oxalkyl while heating the reaction mixture.

85

3. The process which comprises causing an alkaline inorganic alkali forming metal compound to act upon an aqueous solution of 1-methyl-5-chlorobenzene-2-carboxyamino-3-thioglycollic acid while heating the reaction mixture.

90

4. The process which comprises heating an aqueous solution of 1-methyl-5-chlorobenzene-2-carboxyamino-3-thioglycollic acid in the presence of the hydroxide of an alkali or earth alkali metal to a temperature of about 140° C. in a closed vessel.

95

In testimony whereof, we affix our signatures.
